Application filed February 20, 1894. Serial No. 500,917. Term of patent 3½ years.

To all whom it may concern:

Be it known that I, CLARENCE W. SEDGWICK, a citizen of the United States, residing in the city of New York, county and State of New York, have invented and produced a new and original Design for a Pocket-Box, of which the following is a specification.

The accompanying drawings represent an oblong box embodying my design and consists as shown in Figure 1, which is a perspective view of said box with the design placed upon it in relief, and Fig. 2, which is a cross section of said design.

The essential features of my design consist of a pocket box provided with the representation of a nude female and a breaking wave with a background of water as shown in the accompanying drawings.

In Fig. 1 A is the metal box, B the female figure, C the wave, D the background of water and e, e, are birds flying in the distance. The female figure B is represented in a semi-reclining position upon the wave c with one hand behind the head, and the other outstretched above the head. The wave c, is represented in the act of breaking while the water D in the background is calm and the birds e, e, appear to be skimming over the surface thereof.

What I claim is—

The design for a pocket box, substantially as herein shown and described.

CLARENCE W. SEDGWICK.
